(57) **CLAIM**

The ornamental design for a telescopic davit structural beam as shown and described.

DESCRIPTION

FIG. 1 is a front perspective exploded view of a telescopic davit structural beam, showing our new design;

FIG. 2 is a front elevation view thereof;

FIG. 3 is a rear elevation view thereof;

FIG. 4 is a left side exploded elevation view thereof;

FIG. 5 is a right side exploded elevation view thereof;

FIG. 6 is a top plan exploded view thereof;

FIG. 7 is a bottom plan exploded view thereof;

FIG. 8 is a front perspective assembled view thereof;

FIG. 9 is a top plan assembled view thereof;

FIG. 10 is a bottom plan assembled view thereof;

FIG. 11 is a left side assembled view thereof; and,

FIG. 12 is a right side assembled view thereof.

The drawings contain symbolic break lines in FIGS. 1 and 4-12. Any portion of the article between the break lines forms no part of the claimed design.

1 Claim, 9 Drawing Sheets
